UNITED STATES PATENT OFFICE.

ALBERTO I. WOODRING, OF WATERLOO, IOWA, ASSIGNOR TO NATIONAL SAFETY DEVICES COMPANY, OF WATERLOO, IOWA.

PERCUSSIVE DEVICE.

Application filed February 13, 1926. Serial No. 88,143.

My invention relates to improvements in percussive devices, and the object of my improvement is to supply a simple, easily controlled device of this class adapted to produce rapid percussive impacts upon a sonorous body for signaling purposes.

This object I have successfully accomplished by the means which are hereinafter described and claimed, and which are illustrated in the accompanying drawings, it being understood that changes in the precise embodiment of invention herein disclosed can be made within the scope of what is claimed without departing from the spirit of the invention.

In said drawings, Fig. 1 is a full sized view of my percussive device, including its manually and resiliently controlled operating valve, parts being shown in side elevation and parts in medial vertical longitudinal section or broken away, the dotted lines indicating a changed operative position of the percussor. Fig. 2 is a plan view of the percussive device alone, the full and dotted outlines of the percussor indicating opposite limits of travel thereof with relation to the periphery of an apposed gong.

The device is particularly appropriate for employment as a sounding warning signal upon a vehicle, such as a street-car or the like, and is intended and designed for using compressed air or other fluid under pressure for its motive power.

The percussive device comprises a hollow cylinder 1 which is open at one end and closed at the other, but the closed end has a relatively small inlet-port 5 in the cylinder boss 4, and which communicates with a threaded socket of larger bore 6 in said boss, the latter receiving a threaded nipple 7 from an elbow-coupling 8 which communicates with a pipe 9, and the latter by an elbow coupling 10, pipe 11 and threaded nipple 12 communicates with a supply-port or passage 36 leading from a central chamber 35 in a valve chamber 27.

The operating valve-chamber 27, while included in the combination of this invention, is not specifically claimed or particularly described herein, being otherwise patented in my United States Patent No. 1,511,554 of October 14, 1924.

The cylinder 1 has and is supported dependingly upon hangers 2 from any sup-

port. A cup-shaped plunger 13 is fitted 55 within and to reciprocate within the interior hollow 3 of the cylinder 1, and has a front closing wall 17 for the open end of the cylinder with an annular stop 18 which at one limit of reciprocation contacts with the front 60 end of the cylinder. This annular end part 18 terminates in a frustal part 19 which serves as an interior centering member for one end of a coiled compression spring 21 which is mounted around a diminished ham- 65 mer part 20 and engaged between said annular part 18 and the inner wall of a U-shaped bracket-member 22, whose end parts embrace opposite sides of the cylinder body in fitting flattened bosses 25 thereon and is se- 70 cured by set-screws 24. The hammer part 20 traverses a bearing-aperture 23 in the cross-part of the member 22 to project there- 75 beyond toward and ordinarily spaced from the edge of a resonant gong 26. The inter- space is such, that at its outer limit of reciprocation, the hammer 20 contacts impact- 80 yingly with said gong.

A number of radial holes 14 are made in the plunger wall 13 about midway of its 80 length to the central hollow 16 of the plunger and terminate outwardly in a shallow annular groove 15 around the plunger at that location, and a narrow seepage passage 45—46.

Referring now to the operating valve- 85 chamber 27, it has a passage 28, interiorly threaded, for communication with some con- 90 duct to a supply of air or other suitable fluid under compression but not shown. In the lower part of the valve-chamber is a lower chamber 29 having a valve-controlled com- 95 munication 34 with the upper chamber 35. A valve-head 31 mounted on a stem has the latter adjustably mounted on a cup-device 30 and a coiled compression-spring 32 bears against the lower part of the latter tending to keep the valve 31 closed. The upper part of the valve-body which traverses said pas- 100 sage 34 terminates upwardly in a short fin- ger or boss 37 which when in its upper position is spaced from the lower end of the bore 39 of a plunger 40 whose upper part is seated in a bearing opening in the upper part of the valve-chamber to project outwardly 105 therefrom, the bore 39 turning laterally into communication with the atmosphere when the plunger is up. A pair of arched stand-

ards 41 have a pintle 42 on which is pivoted a pedal 43 which has its lower edge shaped as a cam 44 to contact with the plunger 38.

To ring the gong 26, the pedal 43 is depressed with the plunger 40, which pushes down the valve parts 37—31, and compressed air passes through the chamber 35 and conduit 9 to the cylinder 1. The plunger 13 is pushed outwardly to expose the annularly connected ports 14, while the spring 21 is compressed, and the hammer 20 rings the gong 26. The air escapes more rapidly through the ports 14 than it enters through the inlet 4, so that the cylinder is immediately emptied of air to about atmospheric pressure. The quick escape of the cylinder air through the ports 14 is expedited by the use of the circumferential groove 15, as the advancing edge of the latter opens the groove 20 all around at once with a wide delivery opening for the ports 14, which could not occur without some delay were the groove omitted, for in the latter case but a small area of each port would be opened instantly, the response 25 of the plunger in reversing being delayed. The spring 21 returns the plunger closing the ports 14.

The narrow grooves 45—46 in the plunger 13 and its fillet 18 are provided to permit a slight seepage of air from the cylinder and is useful in case of a small leakage of air through the operating valve, preventing the building up in the cylinder of air pressure from such leakage between outward reciprocations or when the valve 27 or any other type of operating valve is leaky.

In the valve-chamber 27, the plunger 40 has an annular flange and between this flange and the bottom of the chamber 35 is mounted a coiled spring 38, which, when the pedal 43 is released, lifts the plunger and by the bore 39 exhausts the air from the chamber 35, so that the lower spring 32 may return the valve 31 to its seat.

45 It should be noted, that no portion of the outer atmosphere can enter the cylinder 1, because the ports 14 can pass only compressed air from the cylinder out through the plunger, for the quick closing of the 50 ports on the return stroke prevents admission of the outer air, and thus no atmospheric dust can pass into the cylinder as in some other kinds of like devices, to foul the cylinder and gradually render it inoperative.

55 Having described my invention, what I claim as new, and desire to secure by Letters Patent, is:

1. In a device of the character described, a cylinder having an open and a closed end,

the latter having a relatively small inlet port 60 in controlled communication with a source of fluid under pressure, a cup-shaped plunger fitted within and to reciprocate in said cylinder and having an outer striker stem, a compression spring anchored to resiliently engage the outer end of said plunger, said plunger having a medial groove around it and having holes leading from said groove to the interior of the plunger, the open end of the plunger being in communication with the cavity of the cylinder, said groove filling with fluid under compression to exhaust the fluid quickly when the groove is uncovered in the outward movement of the plunger, the spring reacting to return the plunger to close said groove upon partial exhaustion of the fluid under compression in the cylinder cavity, whereby the spring is kept in partial compression during the reciprocations of the plunger, and the reciprocations of the plunger are limited in their length to approximately 70 the width of said groove to produce rapid 75 blows by the said striker stem upon a resonant device.

2. In a device of the character described, a cylinder having an open and a closed end, the latter having a relatively small inlet port 80 in controlled communication with a source of fluid under pressure, a cup-shaped plunger fitted within and to reciprocate in said cylinder and having an outer striker stem, a compression spring anchored to resiliently engage the outer end of the plunger, said plunger having a medial groove around it and having holes leading from said groove to the interior of the plunger, the open end of the plunger being in communication with the cavity of the cylinder and the plunger having a minute longitudinal groove leading 85 from said medial groove outwardly for constant communication with the atmosphere, said medial groove filling with fluid under compression to exhaust the fluid quickly when the groove is uncovered in the outward movement of the plunger, the spring reacting to return the plunger to close said groove upon partial exhaustion of the fluid under 90 compression in the cylinder cavity, whereby the spring is kept under partial compression during the reciprocations of the plunger, and the reciprocations of the plunger are limited in their length to travel approximately 95 the width of said groove in opening and closing it, to thereby produce rapid blows by the striker stem upon a resonant device.

In testimony whereof I affix my signature.

ALBERTO I. WOODRING.
